VALVE

August L. Segelhorst, Huntington Beach, and
Lewis F. Davis, Santa Ana, Calif., assignors to
Wm. B. Shaffer, Brea, Calif.

Application November 19, 1930, Serial No. 496,642

3 Claims. (Cl. 251—159)

This invention is a valve particularly applicable as a blow-out preventer for oil wells and the like; and has for its object to provide a valvular means which normally has an open unobstructed bore but which is readily operated for concentrically closing its bore, with packing preferably provided at the closure means and adapted for positive actuation so as to insure a tight seal.

More particularly it is an object of the invention to provide a valvular means comprising diametrically opposite and radially shiftable closure elements adapted when moved away from one another to define a normal open bore and adapted to close said bore when moved toward one another, with operating mechanism providing a positive means for simultaneously and equally shifting the closure elements so as to maintain a concentric bore during shifting of the closure elements.

It is a further object of the invention to provide packing for the closure elements adapted to form a fluid-tight seal and longitudinally operatively expanded by the radial abutment of the closure elements when the latter are in closed position.

It is a still further object of the invention to mount the valvular means in well casing or the like and recess the proximate faces of the cooperating closure elements so that when in closed position they will encircle and snugly engage drill pipe which extends into the well and thereby shut-off the bore of the casing in the event of a blow-out, with the cooperating closure elements when in open position spaced radially from the drill pipe so as to provide an unobstructed open bore for the well casing.

Further objects of the invention will be readily understood from the following description of the accompanying drawing, in which:

Fig. 1 is an axial section through well casing showing the improved valve operatively assembled.

Fig. 2 is a transverse section on the line 2—2 of Fig. 1.

Fig. 3 is a section on the line 3—3 of Fig. 2.

The valve may be employed wherever a tight shut-off for a bore is desired, but is particularly applicable and is herein shown and described as a blow-out preventer for an oil well or the like, for which purpose the valve is mounted between adjacent lengths of usual well casing 1 which is adapted to receive a usual string of drill pipe 2.

The valve preferably comprises cooperating and laterally projecting casing sections 3—4, adapted for flanged abutment as shown at 5 and 55 preferably connected by bolts 6, with aligned

bosses 7 at the outer faces of the casing sections connected to proximate lengths of well casing by means of studs 8.

Cooperating closure elements 9—10 are slidably mounted in the valve casing for movement transversely of the axis of the well casing, and for this purpose one section of the valve casing, shown as section 4, is recessed so as to form a closed transverse guideway 11 adapted to slidably receive the elements 9—10, with the closure elements retained in the guideway by the overlying and cooperating casing section 3; and the closure elements preferably slidable on ribs 12 at the inner faces of casing sections 3—4, with said ribs preferably merging into annular seats 13 in alignment with bosses 7, and the bores 14 of said annular seats opening through the casing sections 3—4 for communication with the proximate lengths of the well casing.

The closure elements 9—10 are adapted for dependent shifting in guideway 11, for abutment of the proximate ends of the elements at an axial plan of bores 14 for closing said bores or opposite shifting of the elements away from one another so as to open the bores; and in the illustrated embodiment of the invention wherein the drill pipe 2 projects through bores 14, the proximate ends of the closure elements instead of forming straight abutment surfaces extending the entire width of said elements, so as to close the entire area of bores 14, are medially recessed or incurved as shown at 15 with radial surfaces 16 beyond the respective ends of said recesses, whereby the surfaces 16 are adapted for diametrical abutment when the valvular means is closed, with the recesses 15 cooperating to define a bore which fits around the drill pipe 2.

The mechanism for dependently shifting the closure elements is adapted to simultaneously and equally shift said elements as to the drill pipe 2 during opening and closing of the valvular means; and as an instance of this arrangement one of the closure elements, shown as element 9, may be formed with a guide frame 17 projecting lengthwise of casing 3—4 and adapted for sliding movement in guideway 11, with the cooperating element 10 slidably mounted in the guide frame which terminates in a cross head 18 in back of element 10, and actuating mechanism engaging the cross head 18 and the element 10 for dependently oppositely shifting the cooperating closure elements.

The actuating mechanism is shown as a shaft 19 journaled in the end of casing 4 in back of cross head 18 and held against longitudinal move-

ment by thrust collars 20, with the inner end of the shaft forming a screw 21 which is threaded through cross head 18, and a screw 22 which projects from closure element 10 adapted for telescopic threaded reception in a bore of the screw 21, with the screws 21-22 oppositely threaded for opposite shifting of closure elements 9-10 responsive to rotation of shaft 19, and the screws being adapted to equi-distantly shift the oppositely moving closure elements.

It will thus be seen that rotation of shaft 19 in one direction is adapted to retract the closure elements 9-10 in their casing 3-4 so as to leave the bores 14 unobstructed except for the depending drill pipe 2, while opposite rotation of shaft 19 will move the closure elements toward one another so as to firmly abut at their surfaces 16, with their recesses 15 fitting snugly around drill pipe 2 so as to completely shut-off the bores 14, and the bore defined by the closure elements at closing moment maintained concentric with bores 14 and the drill pipe 2, due to the simultaneous and equal opposite shifting of the closure elements by their dependent operating mechanism. The shaft 19 may be rotated by any suitable means, and is preferably adapted for remote control as for example by a shaft 25 having universal joints 26, and preferably provided with a manual actuating means (not shown).

The valvular means as thus described is preferably provided with packing adapted to form a fluid tight seal, with the packing preferably operatively expanded by the abutment of cooperating closure elements 9-10 and adapted to form a radial seal between the cooperating elements and also provide a longitudinal seal between the closure elements and the casing 3-4.

For this purpose the packing which is preferably of a flexible resilient material such as rubber, may be mounted in closure elements 9-10 so as to project beyond the surfaces 15 and 16 of said elements, and responsive to radial pressure against the packing resulting from the abutment of the cooperating surfaces 16 and the engagement of surfaces 15 with drill pipe 2, the packing is adapted for longitudinal expansion beyond the faces 30-31 of the closure elements which engage the ribs 12 and seats 13 of the respective casing sections 3 and 4. As an instance of this arrangement each of the elements 9 and 10 is semi-circularly recessed at the medial portion of its abutment surfaces 15-16 and between its faces 30-31 as shown at 32, with said recess opening through the faces 30-31 adjacent the periphery of the semi-circular recess as shown at 33, and the recessed closure element forming an integral structure as a result of connecting ribs 34 projecting from the peripheral wall of recess 32 with the top and bottom of the ribs spaced from the semi-circular openings 33 as shown in Fig. 1, and the ribs terminating in partitions 35 extending upwardly and downwardly to the walls of the closure element and formed integral therewith, with the partitions 35 preferably terminating just short of the abutment surfaces 15-16.

The packing for each closure element is preferably molded in place and fills the recess 32 around the ribs 34 and the partitions 35 as shown at 37, with the packing preferably projecting slightly beyond and following the contour of abutment surfaces 15-16 as shown at 15a-16a, and extensions 37a of the packing fill the openings 33 with the outer surfaces of said exten-

sions normally flush with the faces 30-31 of the closure element. It will thus be seen that with the elements 9-10 in closed position, the abutment of the cooperating surfaces 16a of the packing of the respective closure elements, together with the abutment of packing surfaces 15a against drill pipe 2, will tightly seal off the closure elements relative to the drill pipe, and the radial pressure against the packing responsive to the shifting of the closure elements to tightly closed position, longitudinally expands the packing 37a beyond the faces 30-31 for tight sealing engagement with seats 13.

In order to direct maximum radial pressure against the peripheral portion of the packing from which the extensions 37a project, and thereby insure operative longitudinal expansion of said extensions, the ribs 34 and partitions 35 are preferably approximately radially disposed, but the ribs and partitions which are adjacent the sides of the closure element as viewed in Fig. 2 and which are designated 34a and 35a, are preferably offset from exact radial alignment so that the projecting ends of the partitions are laterally spaced beyond true radial lines A, and the pressure exerted against both faces of the ribs and partitions thus provides a wedging action for squeezing the packing toward its peripheral portion from which the extensions 37a project. In order to insure uniform operative expansion of the entire peripheries of extensions 37a, the portions of partitions 35 projecting above and below the ribs 34 preferably convergently taper at their inner ends as shown at 39 so that substantially uniform pressure is exerted against the entire peripheral portion of the packing from which the extensions 37a project; and in order that maximum longitudinal expansive force may be directed against extensions 37a, the walls of the closure element preferably form undercut shoulders 40 at the openings 33, and said shoulders may taper toward said openings as shown at 41.

The invention thus provides a valvular means particularly adapted for use as a blow-out preventer for oil wells, and adapted for dependent and equal opposite shifting of cooperating closure elements so as to define an open unobstructed bore or completely close said bore, preferably around a centrally disposed drill pipe, and the closed bore tightly packed-off both radially and longitudinally by a sealing medium which is operatively expanded by the abutment of the cooperating closure elements.

We claim:

1. A valve comprising a casing, cooperating closure elements adapted for relative opposite sliding movement in the casing to open or close a bore, means for oppositely shifting the closure elements, the proximate surfaces of the closure elements being semi-circularly recessed concentric with the proximate surfaces of the closure elements with the bases of said recesses opening through the walls of the closure elements which slidably engage the casing, ribs in said recesses integral with the closure elements and projecting forwardly from the bases of said recesses approximately radially to said recesses but with the forward ends of next adjacent ribs laterally spaced slightly beyond radial lines, and packing molded in said recesses around the ribs and projecting through said openings, the packing on the cooperating closure elements being adapted for abutment when the bore is closed so as to radially seal said bore and longitudinally 75

expand the packing through said openings for sealing engagement with the casing.

2. A valve comprising a casing, cooperating closure elements adapted for relative opposite sliding movement in the casing to open or close a bore, means for oppositely shifting the closure elements, the proximate surfaces of the closure elements being recessed with the bases of said recesses opening through the walls of the closure elements which slidably engage the casing, ribs in said recesses integral with the closure elements and projecting forwardly from the bases of said recesses in spaced relation from said walls of the closure elements and terminating at their forward ends and in front of the openings at the bases of the recesses in partitions extending longitudinally to the said walls, the rear ends of said partitions convergently tapering longitudinally beyond the ribs, and packing 20 molded in the recesses around the ribs and par-

titions and projecting through the said openings, the packing on the cooperating closure elements being adapted for abutment when the bore is closed so as to radially seal said bore and longitudinally expand the packing through said openings for sealing engagement with the casing. 5

3. A valve comprising cooperating closure elements adapted for relative opposite sliding movement to open or close a bore, means for oppositely shifting the closure elements, the proximate surfaces of the closure elements being recessed, radial; spaced ribs in each of said recesses integral with the closure elements and projecting forwardly from the bases of said recesses, and packing molded in the recesses around the ribs 15 and projecting beyond the proximate surfaces of the closure elements for sealing abutment when the bore is closed. 10
